UNITED STATES PATENT OFFICE

2,270,809

MASONRY BUILDING UNIT

Robert Lee Kaye, Newark, N. J.

Application April 15, 1941, Serial No. 388,689

9 Claims. (CL 20—5)

The present invention is concerned with improvements in building units of the general type disclosed in United States Letters Patent Number 2,224,351 granted to me December 10, 1940.

The body of the unit is composed of fiber board of one type or another usually of a high percentage of cellulose. The unit is frequently used as a veneer or the like for the external walls of buildings, but as readily lends itself to interior paneling or the like.

It is an object of the invention to provide a building unit which will simulate a continuous masonry wall or the like.

It is an object of the invention to provide a building unit which will present a continuous pattern made up of a plurality of units the surface texture of which are such that the joints between units blend into the wall as a whole and the uninterrupted continuation of the pattern is obtained with the resultant effect of solidity.

It is an object of the invention to provide a building unit with a design impressed therein or overprinted thereon in such a manner that with all units identical, different parts of the units match and a continuous surface is presented.

It is an object of the invention to provide a unit having surface texture and tone which yields a softened weathered effect.

Other objects and desiderata will appear in the following description—

Figure 1 is a plan view of one form of my improved unit with phantom views of additional units in place and matching.

Figure 2 is an enlarged sectional view along line 2—2 of Figure 1 with certain portions shown full size.

Like numerals refer to like parts throughout.

A board 10 of fiber, cellulose or similar material is dried to remove moisture and is then impregnated with hot waterproofing compound such as asphalt, tar, wax, one of the paraffins or the like. The impregnation may saturate the board if desired, but normally is of the character termed "surface impregnation". Various means for driving the waterproofing material deeper in certain localized portions may be used. One is disclosed in my above mentioned patent.

The impregnated unit is then baked and passed through a pair of calendering rolls. The back may be impressed with inverted beads as described in the patent thus giving added strength and rigidity by driving the waterproofing compound deeper where it can cement additional fibers together. The absorbed compound is shown at 11 in one form it might take.

A suitable mastic such as filled asphalt, cement mixtures, tar or the like 12 is applied to the outer surface of impregnated board 10 and granules 13 of crushed slate, rock or other suitable material are sprinkled thereon or applied thereto.

The board is then passed through a pair of impress rolls and depressions 14 are made in the mastic covered face of board 10. Depressions 14 are preferably about $\frac{1}{8}$ " deep and $\frac{1}{8}$ " wide at the bottom. Intermediate rounded portions 15 have an $\frac{1}{8}$ " radius. The above dimensions of elements 14 and 15 have been chosen as best suitable for units of $43\frac{1}{2}$ " by $14\frac{1}{2}$ " used on and in residences or the like. Other dimensions and spacing may of course be used without departing from the spirit of the invention.

Depressions 14 are preferably not so deep that the granules 13 at the bottom thereof are hidden or buried in the mastic 12. Rounded portions 15 and depressions 14 give a soft surface texture to the unit which in a measure simulates the effect of weathering. This toning effect is especially valuable where substantial areas of different colors are used as in mosaics. The different colors may be on the same unit 10 or the units may differ as to material color and design. I have developed a device for depositing such mosaic patterns with intricate color designs where toning and texture are of considerable importance.

Another and very important point in connection with depressions 14 and beadings 15 is that while they give texture and tone to the surface they make the joints between units substantially invisible. The effect has much in common with surface shading on drawings and as frequently occurs therein the lines need not be horizontal nor need they all be parallel. The result yields an effect of solidity which is most compelling and gives a touch of authenticity to the whole.

After the depressions 14 and beadings 15 are formed the unit 10 is passed between a pair of embossing rolls which may be heated if desired. These rolls form joints 16 and give a masonry pattern.

If desired the joints 16 may not be pressed quite so deeply and additional granules of a color simulating mortar may be rolled thereon. Any excess may be lifted by vacuum.

It will be noted that the pressure of the impress or embossing rolls in forming joints 16 drives the waterproofing compound deeper along these lines as at 17. The fiber cementing action of this compound not only strengthens and

rigidifies the unit as whole, but also furnishes stronger and better nailing areas.

The best and least conspicuous nailing areas are the joints 16 since the nail heads are below the surface of the remainder of the unit. In addition because of the deeper penetration of the waterproofing compound at these joints and its resulting fiber cementing action not only do the strengthened fibers grip the nailing unit with a greater firmness than otherwise, but they also resist the softening action of any moisture which may penetrate the unit due to the nail hole or the like. As a result the firm gripping action of the fibers is continued for a long period.

The joints 16 outline masonry elements 18 which simulate stone or the like. One important feature is the positioning of the edge portions of elements 18 and joints 16 so that they will match the proper parts of other units as shown in outline at 19 in Figure 1. For example the bottom edge of element 20 fits the upper edge of element 21 as shown. The same is true for elements 23 and 24 as well as the ends of the units.

With this arrangement the units 10 may all be made identical and form part of a continuous pattern or a random masonry wall. The above showing and description is to be taken as illustrative of the invention and not as limiting. The depressions 14 and beadings 15 in Figure 2 have been made full size for clarity. Normally about thirty-five beadings 15 are used on a unit 10. The units are normally shiplapped as at 25, and may be given an acute angle at 26 to insure meeting at the outer edges.

The effect of depressions 14 may be obtained by cutting the granule covered mastic surface with suitably shaped knives or raking it with a member having projecting fingers. The depression lines 14 may be made to wave or undulate or may be discontinuous either all together or selected lines at selected intervals.

Again the granules 13 may be positioned on the face of the unit 10 in narrow elongate rows and then rolled in place. The dark background would show through the spaces between rows where the granules 13 were thinner. The whole face would preferably be covered with the granules, but the coverage would be uneven and thus give the shading, weathered or softened effect which blends adjacent units together and gives the effect of a solid wall, roof or other surface.

I claim:

1. In a fiber board building unit, a base member impregnated with a waterproofing material, a series of narrow, elongate, substantially parallel projections on one face of said unit said projections being relatively close together and running substantially continuously over the entire face of said unit and so arranged that they mate substantially with similar projections on a next adjacent unit.

2. A fiber board building unit, a base member impregnated with a water proofing material, a series of narrow, elongate depressions in a face thereof said depressions being relatively close together and running substantially continuously over the entire face of said unit and so arranged that they mate substantially with similar depressions on a next adjacent unit.

3. A fiber board building unit, interconnecting depressions on a face thereof representing mortar joints with irregular masonry elements therebe-

tween, said masonry elements being so positioned on said unit that edges of said elements at the edges of said units match and fit with other edge portions of elements when adjacent units are displaced a predetermined amount in making up a wall whereby an irregularly shaped and apparently random solid masonry element is formed having parts in contiguous units, at least one of such elements on the upper and lower longitudinal edges of a unit.

4. In a fiber board building unit, a base member impregnated with a waterproofing material, a mastic material on one face of said member, crushed granular material adhered to said mastic, said granular covered mastic being divided into masonry simulating portions having mortar joints therebetween, relatively narrow elongate depressions running over the surface of said granular covered face, said depressions being closely adjacent each other and substantially continuous from masonry simulating portion across intervening mortar joints to masonry simulating portion to an edge of said unit and so arranged that they mate substantially with similar depressions in a next adjacent unit whereby a shading effect is obtained, yielding a softened weathered surface texture which blends a plurality of such units into a single solid continuous surface.

5. The combination set forth in claim 4, said depressions being shallow with the granular material at the bottoms thereof visible.

6. The combination set forth in claim 2, granules adhered to said face, said depressions being shallow with the granules at the bottoms thereof visible.

7. The combination set forth in claim 3, relatively narrow elongate depressions in close side by side relation running over the masonry simulating face of said unit, said depressions being substantially continuous from masonry element across intervening mortar joints to masonry element to an edge of said unit and so arranged as to substantially mate with similar depressions in a next adjacent unit whereby a shading effect is obtained, yielding a softened weathered surface texture which blends contiguous units into a single solid continuous surface.

8. In a fiber board building unit, a base member impregnated with a waterproofing material, a mastic material on one face of said member, crushed granular material adhered to said mastic, said granular covered mastic being divided into masonry simulating portions having mortar joints therebetween, said granules comprising relatively narrow elongate granule groupings running over the surface of said granular covered face, said groupings being closely adjacent to each other and substantially continuous from masonry simulating portion to masonry simulating portion to an edge of said unit and so arranged that they substantially mate with similar groupings on a next adjacent unit whereby a shading effect is obtained, yielding a softened weathered surface texture which blends a plurality of such units into a single solid continuous surface.

9. The combination set forth in claim 3, relatively narrow elongate rows of granules in close side by side relation on said masonry simulating face, said rows being substantially continuous from masonry element across intervening mortar joints to masonry elements.

ROBERT LEE KAYE.
